OF CHICAGO, ILLINOIS

OSCILLATING FAN

Application filed April 18, 1929. Serial No. 356,086.

My invention relates in general to fans and has more particular references to a novel and improved means for and method of causing fans to oscillate. My invention relates 5 more especially to a means and method particularly adapted for installation in connection with fans simulating air-craft, whereby the same may be caused to oscillate in an extremely life-like manner, by the reaction 10 of the air current produced by the fan against a deflectable steering element.

Air fans made in simulation of airplanes have a particular advantage in that they present a slightly and novel appearance and 15 it is an important object of my invention to provide an air fan formed in simulation of an airplane having means whereby the fan may be oscillated periodically in order to closely simulate the appearance of an air- 20 plane in flight.

Another important object of my present invention is to provide novel and improved means for causing the fan to oscillate.

Another important object of my present 25 invention is to provide a deflectable steering member arranged in position to react against the air currents produced by a fan and novel means for controlling the angularity of the member whereby the fan may be oscillated 30 by an air current set in motion by the operation of the fan.

Another important object is to provide a 35 steering vane arranged in the path of air currents created by a fan and means for periodically deflecting the vane in order to cause the fan to oscillate.

Still another important object of my invention is to provide a shiftable member disposed in the path of air currents created by 40 the operation of a fan and concealed means for changing the angular relationship of the shiftable member, said means being operated by the fan motor.

45 Numerous other objects and advantages of my present invention will be apparent as it is more fully understood from the following description which, taken together with the accompanying drawings discloses a preferred 50 embodiment of my invention.

Referring to the drawings:

Figure 1 is a top plan view of a fan having means, embodying my present invention, for causing the fan to oscillate;

Figure 2 is a section taken substantially 55 along the line 2-2 in Figure 1;

Figure 3 is a perspective view of the oscillating mechanism of the fan illustrated in Figure 1; and

Figures 4 and 5 are sectional views illustrating a modified construction embodying 60 my invention.

To illustrate my invention I have shown on the drawings a fan assembly formed in simulation of an airplane and comprising 65 a motor 11, which in the illustrated embodiment comprises an electric motor, a conical tube 12 simulating the fuselage of an airplane and extending rearwardly of one end of the motor 11 and a strip of suitable material 13 simulating the wings of an airplane secured substantially at its midportions of the motor 11 by means of suitable fastening means, such for instance, the nuts and bolts 14, although it will be obvious that 70 the wings may be soldered or welded or otherwise secured to the motor by other means than the bolts and nuts 14.

Although, for the purposes of illustrating 75 my invention I have shown a fan formed in simulation of a monoplane, it will be obvious that additional wing planes may be added as designed in order to simulate having more than a single wing plane. Thus a second wing plane may be added by securing 80 an additional strip of material similar to the member 13, to the underside of the motor 11 by suitable fastening means. The wings are braced by member 15 extending from the motor 11 to the wings 13 thus further 85 simulating an airplane. At the rear-most end of the fuselage 12, I arrange laterally and oppositely extending members 16 formed in simulation of the tail fins of an airplane. These tail fins may be secured to 90 the fuselage in any convenient manner, such as by riveting, soldering, welding and the like. At the rear-most portion of the fuselage I also arrange a steering member or 95 vane 17 formed in simulation of an airplane 100

rudder. This member is arranged in a plane substantially normal to the planes of the tail fins 16, and of the wings 13 and is pivotally mounted to a pin 18, which in turn is carried in a bracket 19 secured to the fuselage.

The bolts 14 extend upwardly of the wings 13 and form a means to which may be secured a swivel bracket 21 or other suitable supporting device for suspending the fan in operative position.

The shaft of the motor 11 extends forwardly and carries thereon a suitable fan 22, which may be formed in simulation of an airplane propeller. The swivel suspension is formed and arranged to provide suitable electrical connections 23 for supplying the motor with power from a suitable source whereby the motor may be driven in order to rotate the fan 22. The blades of the fan 22 are suitably arranged so that when rotated as aforesaid, it will create a current of air which travels rearwardly past the fuselage 13, tail fins 16 and rudder 17.

It will be obvious that if the rudder is arranged at an angle with respect to the air current a turning movement will be exerted on the fan assembly by the reaction of the rudder to the current of air. If the rudder is arranged to one side of its normal position in the plane of the axis of rotation of the fan, the rear-most portions of the fan assembly will be urged in the opposite direction and vice-versa.

The fan assembly is supported at the lower end of a suitable suspension member which I have shown as a tubular member 24, which may be secured at one end to a suitable supporting base, and which carries it at its lower end, a washer or plug 25 threaded or otherwise suitably secured to the lower end of the tube 24. This plug 25 extends outwardly of the tube and seats in a socket 26 formed in the upper portions of a bracket 27, the lower portions 28 of which are arranged to provide a laterally extending flange provided with bolt holes whereby the bracket 27 may be secured to the motor 11 by means of studs 29, or other suitable fastening means. The plug 25 is retained in the socket 26 by means of a cover plate 31, having a recess in which a ball bearing 32 is arranged. The cover plate 31 and ball-bearing 32 encircles the tube 24 above the plug, and the outer portions of the cover plate are secured to the upper portions of the bracket 27 by bolts as illustrated, to thus secure the supporting tube 24 and the plug 25 rotatably to the bracket 27. It will be apparent that the provision of the ball-bearing 32 between the cover plate 31 and the plug 25 facilitates relative rotation of the supporting tube 24 and the bracket 27. Below the plug housing the bracket is hollow to provide a channel 32. The plug 25 of the

supporting tube 24 also provides a channel coterminous with the channel 32, so that suitable conductors 23 may be arranged in the tube 24 through the swivel connection, and into the channel 32. The channel 32 also is connected with the interior of the fuselage 12 of the fan assembly by means of an insulated conduit 33 in which the conductors 23 are arranged. In this manner the conductors 23 may be entirely concealed at all times in passing from the source of motive power to the motor 11. The swivel connection which I have just described has the advantage of neatness, compactness, simplicity and serviceability; and in addition the conductors 23 are concealed at all times, so that dirt may not affect the insulation, nor will the exposures of the conductors mar the slight appearance of the fan suspension.

It will be noted that I have shown continuous conductors 23 passing through the swivel connection 21 and into the fan assembly. For this reason it is apparent that the swivel suspension, as illustrated, cannot be used for a fan assembly which continuously rotates in operation. It would however be a simple matter to insert to provide cooperating slip contact mounted respectively in the rotating plug 24 and in the stationary bracket 27, whereby a suitable power connection might be maintained, without modifying the remaining structure of the swivel connection 21. I do not illustrate this modification for the reason that the fan assembly of my invention is adapted for oscillatory movement about the support member 24. This oscillatory movement is accomplished in a novel manner and I have illustrated in the drawings, two preferred embodiments illustrating the mode in which a fan assembly may be caused to oscillate in the novel manner of my present invention.

In Figures 1, 2, and 3 on the drawings, I have shown means for alternating the annular relationship of the vane 17 with respect to the path of the air currents set up by the rotation of the fan 22.

The vane 17 is caused to swing about its pivot 18 and assume one or the other of two angular positions by means of a mechanism, which includes laterally extending arms 36 extending oppositely and outwardly from a collar 34 encircling the tube 24 and secured thereto by means of a said screw 35, so that the arms 36 may be swung about the support member 24 and fixed thereto in any desired angular position. The collar 34 is mounted to the support member 24 above the swivel connection 21 and rests upon the upper surface of the cover plate 31. The arms 36 extend outwardly of the collar 34 and are offset first downwardly and then outwardly as at 37. Tie rods 38 are pivotally secured as at 39 to the extremities of the arms 36 and extend rearwardly to form an operating con-

nection with a vane flipping mechanism illustrated generally at 42.

The tail flipping mechanism 42 comprises a relatively flat member pivoted at 45 to a pin supported in an extension of the bracket 19. The member 43 has outwardly and oppositely extending arms, the extremities of which are provided with pegs 46 comprising nuts and bolts extending through apertures formed in the arms of the member 43. The rear-most ends of the tie rods 38 are looped as at 41, around the pegs 46 to thus provide a sliding connection between the ends of the rods 38 and the arms of the pivoted member 43; the pivoted member 43 also carries a peg 48 positioned forwardly of the pivot 45 and a spring 47 connects the peg 48 to a point in the bracket 19, rearwardly of the pivot 45, so that when the member 43 rotates about its pivot 45 in one direction or the other, the spring 47 will resiliently urge the member 43 to maintain its displacement. A second pivot member 44 is mounted to the pivot 45 immediately beneath the member 43. This second member 44 is provided with rearwardly extending curved arms 53, and a forwardly extending arm 55, in which is mounted an upstanding pin 57. The forward extremity of the arm 55 is off-set downwardly as at 59, and is connected by means of spring 61 to a point in the supporting bracket behind the pivot 45, so that when the member 44 is moved angularly in one direction or another about its pivot, the spring 61 will resiliently urge the member to maintain its displacement.

The pin 57 extends upwardly of the member 44 immediately in front of the forward edge of the pivoted member 43. This member 43 is provided with spaced upstanding arms 49 on opposite sides of the pin 57. These arms 49 carry adjustable screws 51 in position to engage the sides of the pin 57, so that when the member 43 is rotated through a predetermined distance in one direction from its normal entered position about its pivot 45, one or the other of the said screws 51 will engage the pin 57 and displace the member 44 about the pivot 45. It will be understood that a slight displacement of the member 44 caused in the foregoing manner will allow the spring 61 to snap the member 44 to the extreme limit of its movement.

The vane 17 is provided with a forwardly extending portion 63, which is arranged in the path of movement of the arms 53 of the member 44, so that when the member 44 is thus rotated about its pivot 45 in one direction or another, one of the arms 53 will engage the vane extension 63 and cause the vane 17 to assume an annular position as illustrated in Figure 1. When this occurs the air current created by the rotation of the fan 22 will cause the rear-most portions of the fan assembly to rotate about the tubular support 24 in a clock-wise direction viewing Fig-

ure 1. Since the arms 36 are fixed to the support 24, such rotation will cause the connecting rods 38 to move the member 43 about its pivot 45 in a counter-clockwise direction viewing Figure 1, until the said screws 51 engages the pin 57 and rotates the member 44 gradually until it assumes a position in which the arms 53 force the vane 17 to assume its second angular position opposite to that shown in Figure 1 of the drawings in which position the reaction of the vane on the air currents produced by the fan 22 will cause the assembly to rotate in a counter-clockwise direction about the supporting member 24. The mechanism may be adjusted to reverse the rotation of the assembly periodically, or after the assembly has rotated a predetermined distance in one direction or the other. This may be accomplished by suitably adjusting the lengths of the rods 38 and the lengths of the loops 41.

It will be apparent that this mechanism is entirely exposed and for this reason I have designed entirely enclosed mechanism for changing the angular relationship of the vane 17 in order to cause the fan assembly to oscillate. This embodiment of my invention is illustrated in Figures 4 and 5 of the drawings. In the embodiment the tail flipping mechanism is enclosed entirely within the fuselage 21. The vane 17 is provided with a forward extension 98, which is connected by means of a suitable pin to the slotted end of an arm 97 of a lever 93, which in turn is pivoted as at 94, in an extension 89 of the bracket 19, said extension comprising a plate extending inwardly of the fuselage 12. The lever member 93 is resiliently urged by means of a spring 95 to assume a position forcing the vane 17 into one of its two angular positions, and suitable means which I will hereinafter more fully describe, are provided whereby the rotation of the motor 11 causes the lever 93 to rotate about its pivot 94 against the tension of the spring 95, and assuming position in which the vane 17 is forced into the other of its two angular positions.

The shaft of the motor 11 is extended rearwardly as at 71 and provided with a worm 73 and wheel 75. The wheel 75 is mounted to a counter-shaft 79, which in turn is journaled in a bracket 77 fastened to and extending rearwardly of the motor 11. This bracket also provides journal support for the worm 73 and a drive shaft 81, which is journaled as at 85 in the bracket 77 and extends rearwardly and is journaled at its opposite end at 87 in the extension 89. At its forward end the shaft 81 is provided with a bevel gear driving connection 83 with the counter shaft 79, and is provided at its opposite end with a worm gear 107, which meshes with a worm wheel 105. The worm wheel 105 is suitably connected for driving a shaft 103 which also carries a cam member 101 in position to engage

and actuate a cam follower 99. This cam follower is mounted in the vane flipping lever 93, so that upon rotation of the cam member 101, the lever 93 may be periodically shifted to cause the vane to move. In this manner and by varying the configuration of the cam member 101, the fan assembly may be caused to reverse its rotation about the support member 24 after any predetermined or desired time interval.

It is thought that the invention and numerous of its manifest advantages will be fully understood from the foregoing description, and it is obvious that numerous changes may be made in the form, construction and arrangement of the various parts without departing from the spirit and scope of the invention, or sacrificing any of its material advantages, the form hereinbefore described being of a preferred embodiment for purposes of illustrating my invention.

Having thus described my invention, what I claim as new and desire to secure by Letters Patent is:

1. A fan assembly comprising a motor having a forwardly protruding shaft, a fan mounted to the shaft, a tubular fuselage extending rearwardly of the motor, a rudder pivoted to the fuselage and means actuated by the motor and enclosed by the fuselage for periodically changing the angularity of the rudder with respect to the fuselage.
2. A fan assembly comprising a motor having a forwardly protruding shaft, a fan mounted to the shaft, a tubular fuselage extending rearwardly of the motor, a rudder pivoted to the fuselage and means actuated by the motor and enclosed by the fuselage for oscillating the rudder, said means comprising a rotatable shaft housed within the fuselage and geared to the motor shaft.
3. A fan assembly comprising a motor having a forwardly protruding shaft, a fan mounted to the shaft, a tubular fuselage extending rearwardly of the motor, a rudder pivoted to the fuselage and cam means actuated by the motor and enclosed by the fuselage for periodically deflecting the rudder.
4. A fan assembly comprising a frame including an elongated tubular portion formed in simulation of the fuselage of an airplane, means for pivotally supporting said fuselage, a fan mounted for rotation at one end of the fuselage, a vane pivotally mounted at the other end of the fuselage in the path of air currents created by the rotation of the fan, means mounted in the fuselage for causing the fan to rotate and means housed within the fuselage for changing the angularity of the vane with respect to the air currents, first in one direction and then in another, whereby to cause the fan assembly to be oscillated on its pivot by the reaction of the air currents on opposite sides of the vane.

5. A fan assembly comprising a frame

formed in simulation of an airplane including wings, hollow fuselage, propeller and a pivoted rudder, means for pivotally supporting the frame, a motor mounted in the frame for rotating the propeller to create a current of air rearwardly past the rudder and means housed within the fuselage and driven from the motor to shift the rudder from side to side, whereby to impart an oscillating movement in the frame about its pivot when the air currents alternately strike opposed sides of said rudder.

In witness whereof, I have hereunto subscribed my name.

FRANK H. GALLAGHER.
